UNITED STATES PATENT OFFICE

PHILIP S. HARPER, OF CHICAGO, ILLINOIS

GAS COCK

Application filed April 4, 1928. Serial No. 267,223.

This invention consists of a double gas range cock having two nozzles for use with a double gas burner, said cock having a particularly advantageous arrangement of ports therein so as to provide improved functioning of such burner and cock.

In this invention I have arranged a double burner and gas cock wherein in one position of said cock both sections of the double burner are on full, and in deviating from such position in either direction both sections are lowered simultaneously, thus giving a uniform frying heat. And I have provided two stops in said cock so that when the turning element is against one stop the gas flow is entirely cut off, and when against the other stop the gas flow to only one section is cut off, the other section being on full. And I have devised a means of lowering the flame in the latter section alone by turning away from said stop, and without danger of gas being turned inadvertently into the former section, by having a point where the gas supply is entirely cut off between the point of full on for both sections and the point against the stop for full on for the one section.

The object of this invention is to provide a double burner which may be quickly and easily turned from two sections burning to a single section burning.

Another object is to provide a double burner in which both sections may be turned to a very slow point simultaneously to give a uniform or frying heat.

Another object of this invention is to provide a double burner in which the flame may be lowered to the minimum practical point with only one section burning.

Another object of this invention is to provide a double burner which is simple in operation.

Another object of this invention is to eliminate the need for any indicating means other than the usual stop at the extreme positions of the turning member, so doing away with the complication and cost of such means as shown in my co-pending application Serial No. 191,643, filed May 16, 1927, which has resulted in Patent No. 1,707,007 issued March 26, 1929.

These and other objects of my invention will be more apparent from the following description and from the drawings, in which—

Figure 1 is a sectional elevation of a gas cock and burner of the type of this invention;

Figure 2 is a cross section of the cock on line 2—2 of Figure 1;

Figure 3 is a cross section through the center of the cock on the line 3—3 of Figure 1; and

Figure 4 is a front view of three of these cocks on a range showing the operation of the handles to provide the different functions of the burner of this invention.

Referring now to the drawings, a manifold pipe 10 is shown, into which is screwed one end of the gas cock body 11, said end having a passage 12 therein which terminates at the plug opening 13 in the gas cock body 11 and into which a tapered plug 14 is fitted, the said plug surface and the bearing surface of the body member 11 being ground to form an accurate fitting joint as in the usual gas cock. The plug 14 has a transversely extending passage 15 therein which is larger at one side of the plug than at the other.

A vertical extension 16 and a horizontal extension or nozzle end 18 are provided integral with the body member through which an L-shaped passage 17 extends, the outer end of which is enlarged for accommodation of the nozzle needle 19. Said needle is slotted longitudinally so that gas may pass from passage 17 on each side of said needle. On the threaded nozzle end 18 there is screwed cap 21 having in its outer end a centrally placed restricted orifice 22. This needle 19 in combination with the nozzle cap 21 forms an adjustable nozzle, and the cap 21 is screwed more or less onto the threads of the nozzle end 18 causing the needle to enter the orifice 22 if conditions require so as to throttle this orifice.

Returning now to the passage 15 in the plug, a passage 23 leads off therefrom and out of the bottom of the plug and into a passage 26 in a nozzle end 27 having a needle 28 and a nozzle cap 29 with a restricted orifice 30, all of the same construction as the before mentioned needle 19, cap 21 and orifice 22 except that orifice 30 is smaller than orifice 100

22 to feed gas to a smaller port area as shown in the drawings. The orifice 30, as shown, is also very small in area compared to the port areas through the plug, so that except for orifice 30 flow of gas is practically unimpeded when the ports in the plug register even partially with corresponding ports in the casing. A stopper plug 31 serves to close the outer end of passage 15, being screwed, 10 pressed, or otherwise securely fastened to effectively close this passage 15.

The upper end of the plug 14 has an extension 40 which extends through a coil spring 42, and a nut 43 which is screwed onto 15 the body 11 at point 44, the spring 42 in this assembly being compressed by the nut 43 against the shoulder 45 on the plug 14, thus serving to hold said plug firmly seated on the bearing surface 13. A stop pin 46 is pressed 20 into said plug as shown in Figures 1 and 2, and said pin operates against a projection 47 of the body 11, said projection determining and limiting the number of degrees of possible rotation of said plug 14.

25 The extension 40 has fastened on the outer end a T handle 48b by means of the stove bolt 49, said handle being slabbed and fitting into a depression in the handle (not shown) in order to prevent relative rotation of the two 30 parts.

Referring now to Figure 3, a side passage 50 is drilled into the bearing surface of the plug 14 so as to make connection to passage 15, for purposes hereinafter to be disclosed.

35 As shown, this passage 50 is drilled at more than a right angle to the passage 15, so that full sized passages may be obtained, and still provide the length of seal "y" to be herein-after described.

40 The nozzle caps 21 and 29 project through an outer shutter 51 and an inner shutter 52, said shutters being fastened to the mixer face 53 by the clamping screw 54. Nozzle cap 21 projects into a mixing tube 55 and said mixing tube has side passages 56 leading therefrom into the outer burner section 57 which is of the usual star shape or any other shape desired and has burner ports 58 in the top surface thereof after the manner of the usual construction of gas range burners. The upper nozzle 29 projects into upper mixing tube 59 which in turn leads directly to the boiling burner section 60 which has burner ports 61 in the top thereof. These ports 61 are spaced

45 in a circle or otherwise conveniently arranged to provide a small boiling burner or so-called simmer burner. The air shutter ports are arranged so that by rotation of the outer shutter 51 the air supply to both burner sections is adjusted in proper proportion to the gas burned by each, as disclosed in my co-pending application Serial No. 227,953, filed October 22, 1927.

50 A shield 62 is provided having a hole 63 therein through which the extension 40 pro-

jects, and said shield has indicating dials 64 thereon as shown in Figure 4. In this figure the T handle 48a is shown pointing to the left, which is the off position for both burners, while T handle 48b is pointing upwards 70 giving both sections of the burner on full, while T handle 48c points to the right where the simmer section alone is burning full. In order to lower the flame for frying in both sections it is only necessary to turn handle 75 48b in either direction slightly, while to lower the simmer burner to a very low or warming heat it is only necessary to turn handle 48c counterclockwise a few degrees. Placing the handles in the position shown allows the use 80 of a T type handle which for the same spacing of burners on a stove allows turning through more than the 105 degrees which is approximately the practical limit on a cock of standard arrangement with the plug perpendicular to the line of the gas nozzle. It is also obvious that a lever handle may be used in my construction operating from a point straight upward to a point straight downward through a half turn, and with this possible 85 180 degree rotation, though less than available with the T handle, there is still permitted the economy and simplification of the cock that my invention provides.

As to the operation of my invention, with 90 the T handle in position 48b as shown in Figure 1, gas may pass to both nozzles through ports 15 and 23, thus giving full burning to both sections.

If now the handle is rotated in either direction somewhat, it may be seen by referring to Figure 3, that passage 12 cuts off or nearly cuts off when both passages 15 and 23 have a wide opening, consequently the turning of the plug from this position and the throttling 105 of the gas through the passage 12 will lower the flame in both sections alike giving a uniform frying heat. Referring to Figure 3 it can be further seen that a quarter turn clockwise to the position 48c will leave passage 12 110 approximately half open due to the registering of passage 50 therewith while passage 15 is fully closed, and consequently gas may pass through this half opening and into passage 23, causing the simmer burner to burn with 115 a full flame since a half opening of passage 12 gives substantially a full gas supply to this small burner section, since one half of the area of passage 50 is very much greater than the area of the small orifice 30 in the nozzle 29. A counterclockwise turning will throttle this 120 passage 12 registering with passage 50, and in this way the flame of the small section of the burner is diminished to such a point that the gas may be entirely cut off from said section 125 since the distance y is about $1/64''$ greater than the distance x and still greater than distance z in Figure 3. There is consequently no danger of lowering the flame in the small section of the burner to such an extent that gas 130

will be again turned into the large section without knowledge of the operator, since from the arrangement of ports shown it can be seen that this small section would be turned entirely out, that is, distance y would entirely cover distance z before port 15 would again open. Therefore it is apparent that there is a point between position 48b and 48c of the handle where no gas is flowing to the burner, that is, where the distance y is completely covering the entrance port 12. It might be thought that in turning from the position 48b therefore to the position 48c the entire burner would go out and have to be relighted, but in practice this does not occur, as if the movement is made in any reasonable manner, the expansion of the gas already in the various passages maintains the flame on the burner until gas flow through the passage 12 is reestablished. This provision of a seal y between two ports both designed to register with a single port of gas entrance, said seal y being greater than the diameter z of said single port of gas entrance, is an essential part of this invention.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. In combination, a gas cock and a double gas range burner, said burner having mixing tubes leading to burner sections, said cock comprising a casing with a plug bearing therein, said casing having two gas cock nozzles, each of said nozzles projecting into one of said mixing tubes, each of said nozzles having a restricted discharge orifice therein, said casing having a gas inlet passage therein, said plug having two passages both arranged to at least partially register in different rotary positions of said plug with said gas inlet passage, a seal between the two said passages in said plug of greater circumferential length than the circumferential length of said gas inlet passage whereby gas flow into both of said passages in said plug is interrupted between the points of partial registering of said two passages with said gas inlet passage, said two passages in said plug having their respective central axes over 100° apart in the bearing surface of said plug.
2. In combination, a gas cock and a double gas range burner, said burner having mixing tubes leading to burner sections, said cock comprising a casing with a plug bearing therein, said casing having two gas cock nozzles, each of said nozzles projecting into one of said mixing tubes, each of said nozzles having a restricted discharge orifice therein, said casing having a gas inlet passage therein, said plug having two passages both arranged to at least partially register in different rotary positions of said plug with said gas inlet passage, a seal between the two said passages in said plug of greater circumferential length

in, said plug having two passages both arranged to at least partially register in different rotary positions of said plug with said gas inlet passage, and a seal between the two said passages in said plug of greater circumferential length than the circumferential length of said gas inlet passage, whereby gas flow into both of said passages in said plug is interrupted between the points of partial registering of said two passages with said gas inlet passage, said plug having a discharge opening in its bearing surface and said casing having a passage leading to one of said gas nozzles, said discharge opening in said plug at least partially registering with said passage in said casing leading to one of said gas nozzles at a rotary position of said plug with the aforesaid seal in said plug totally shutting off the aforesaid inlet passage in said casing.

3. In combination, a gas cock and a double gas range burner, said burner having mixing tubes leading to burner sections, said cock comprising a casing with a plug bearing therein, said casing having two gas cock nozzles, each of said nozzles projecting into one of said mixing tubes, each of said nozzles having a restricted discharge orifice therein, the discharge orifice in one nozzle being larger than that in the other, said casing having a gas inlet passage therein, said plug having two passages both arranged to at least partially register in different rotary positions of said plug with said gas inlet passage, and a seal between the two said passages in said plug of greater circumferential length than the circumferential length of said gas inlet passage, whereby gas flow into both of said passages in said plug is interrupted between the points of partial registering of said two passages with said gas inlet passage, said plug having a discharge opening in its bearing surface, and said casing having a passage leading to the one of said nozzles having the larger discharge orifice, said discharge opening in said plug at least partially registering with said passage in said casing leading to said nozzles having the larger discharge orifice at a rotary position of said plug with the aforesaid seal in said plug totally shutting off the aforesaid inlet passage in said casing.

4. In combination, a gas cock and a double gas range burner, said burner having mixing tubes leading to burner sections, said cock comprising a casing with a plug bearing therein, said casing having two gas cock nozzles, each of said nozzles projecting into one of said mixing tubes, each of said nozzles having a restricted discharge orifice therein, said casing having a gas inlet passage therein, said plug having two passages both arranged to at least partially register in different rotary positions of said plug with said gas inlet passage, a seal between the two said passages in said plug of greater circumferential length

- than the circumferential length of said gas inlet passage, whereby gas flow into both of said passages in said plug is interrupted between the points of partial registering of said
- 5 two passages with said gas inlet passage, each of said two passages in said plug having an area at least four times as great as the area of the smaller discharge orifice in said gas nozzles.
- 10 5. In combination, a gas cock and a double gas range burner, said burner having mixing tubes leading to burner sections, said cock comprising a casing with a plug bearing therein, said casing having two gas cock nozzles, each of said nozzles projecting into one of said mixing tubes, each of said nozzles having a restricted discharge orifice therein, said casing having a gas inlet passage therein, said plug having two passages both arranged to at least partially register in different rotary positions of said plug with said gas inlet passage, a seal between the two said passages in said plug of greater circumferential length than the circumferential length of said gas inlet passage, whereby gas flow into both of said passages in said plug is interrupted between the points of partial registering of said two passages with said gas inlet passage, said
- 15 75 plug having a discharge opening in its bearing surface, and said casing having a passage leading to one of said gas nozzles, said discharge opening in said plug at least partially registering with said passage in said casing leading to one of said gas nozzles at a rotary position of said plug with the aforesaid seal in said plug totally shutting off the aforesaid inlet passage in said casing, and stops limiting the turning of said plug.
- 20 8. In combination, a gas cock and a double gas range burner, said burner having mixing tubes leading to burner sections, said cock comprising a casing with a plug bearing therein, said casing having two gas cock nozzles, each of said nozzles projecting into one of said mixing tubes, each of said nozzles having a restricted discharge orifice therein, the discharge orifice in one nozzle being larger than that in the other, said casing having a gas inlet passage therein, said plug having two passages both arranged to at least partially register in different rotary positions of said plug with said gas inlet passage, a seal between the two said passages in said plug of greater circumferential length than the circumferential length of said gas inlet passage, whereby gas flow into both of said passages in said plug is interrupted between the points of partial registering of said two passages with said gas inlet passage, said plug having a discharge opening in its bearing surface and said casing having a passage leading to the one of said nozzles having the larger discharge orifice, said discharge opening in said plug at least partially registering with said passage in said casing leading to said nozzles having the larger discharge orifice at a rotary position of said plug, with the aforesaid seal in said plug totally shutting off the aforesaid inlet passage in said casing, and stops limiting the turning of said plug.
- 25 9. In combination, a gas cock and a double gas range burner, said burner having mixing tubes leading to burner sections, said cock comprising a casing with a plug bearing therein, said casing having two gas cock nozzles, each of said nozzles projecting into one of said mixing tubes, each of said nozzles having a restricted discharge orifice therein, said casing having a gas inlet passage therein,
